United States Patent Office

Des. 221,179
Patented July 13, 1971

221,179

BOWL

Marcel Paquette, 393 Crestwood Drive,
Cheshire, Conn. 06410

Filed May 27, 1970, Ser. No. 23,165

Term of patent 14 years

Int. Cl. D7—01

U.S. CL. D44—15

FIG. 4.

FIG. 1 is an elevational view of a bowl or the like showing my new design, it being understood that the circular ring constituents forming the bowl continue about the entire periphery thereof;

FIG. 2 is a bottom view;

FIG. 3 is a top plan view; and

FIG. 4 is a sectional view taken along line 4-4 of FIG. 1.

I claim:

The ornamental design for a bowl, substantially as shown and described.
